Inventor
Louis A. Morgan

By Lester A. Allman
Attorney

UNITED STATES PATENT OFFICE.

LOUIS ALBERT MORGAN, OF SAFETY HARBOR, FLORIDA.

WRENCH.

Application filed June 9, 1922. Serial No. 567,101.

To all whom it may concern:

Be it known that I, LOUIS A. MORGAN, a citizen of the United States, residing at Safety Harbor, in the county of Pinellas and State of Florida, have invented certain new and useful Improvements in Wrenches, of which the following is a specification.

This invention relates to wrenches, and the primary object of the invention is to 10 provide an improved socket wrench, which can be adjusted to different sizes for receiving different sized nuts, thereby eliminating the necessity of providing a different sized head for each size of nut and the time consumed for picking out the correct sized head for the nut to be acted upon.

Socket wrenches generally come in sets embodying a handle and a plurality of heads of different sizes for acting upon nuts of 20 different sizes, which necessitate the provision of a case for the heads and handle, which adds to the cost and selling price of the wrench.

It is therefore a prime object of this invention to provide a socket wrench embodying a head, means for operating the head, and a plurality of adjustable jaws carried by the head for engaging different sized nuts.

30 A further object of the invention is the provision of an adjustable socket wrench for acting upon hexagonal nuts embodying a head, a plurality of pivoted jaws carried by the head, and an adjusting nut and sleeve for adjusting the jaws in relation to each other, and for holding the jaws against movement when acting on a nut.

40 A further object of the invention is the provision of a novel adjustable socket wrench in which the adjustable jaws thereof can be removed from the head of the wrench when the said jaws become broken or when it is desired to associate a different type of jaw with the head.

45 A still further object of the invention is to provide an improved adjustable socket wrench of the above character, which will be durable and efficient in use, one that will be simple and easy to manufacture, and one 50 which can be placed upon the market at a reasonable cost.

With these and other objects in view, the invention consists in the novel construction, arrangement and formation of parts, as will 55 be hereinafter more specifically described, claimed and illustrated in the accompany-

ing drawings, forming a part of this specification, in which drawings:

Figure 1 is a top plan view of the improved adjustable socket wrench. 60

Figure 2 is a diametric section through the head thereof.

Figure 3 is a bottom plan view of the head of the improved socket wrench.

Figure 4 is a diametric section through the socket wrench, showing the jaws adjusted to their closed position. 65

Figure 5 is a bottom plan view of the head of the socket wrench showing the jaws in their closed position. 70

Figure 6 is a section through the head of the wrench taken on the line 6—6 of Figure 2.

Figure 7 is a section through the wrench taken on the line 7—7 of Figure 2. 75

Figure 8 is a detail elevation of the head or plug portion of the wrench.

Figure 9 is a bottom plan view of the same.

Figure 10 is an edge elevation of one of 80 the jaws of the wrench.

Figure 11 is an inner face elevation of one of the jaws of the wrench.

Figure 12 is a detail section through one 85 of the jaws of the wrench, taken on the line 12—12 of Figure 10, and

Figure 13 is a detail plan view of the adjusting nut for said jaws.

Referring to the drawings in detail, wherein similar reference characters designate corresponding parts throughout the several views, the letter A indicates the head of the wrench; B, the jaws detachably associated therewith; C, the adjusting nut; D, the adjusting sleeve; and E, a means for operating the said wrench. 95

The head A comprises a cylindrical shaped body 10, having an axial bore 11 extending therethrough for the reception of the adjusting bolt 12, which can be provided with 100 a knurled head 13 to facilitate the turning thereof. The body 10 is provided at equidistantly spaced points with longitudinally extending slots 14, in which is adapted to be positioned the shanks of the jaws B, as will be hereinafter more fully described. Adjacent to the upper terminals of the grooves 14, the body 10 is provided with an annular groove 15, the purpose of which also will be hereinafter more fully described. The upper face of the body 10 can be provided with 105

suitable means for permitting the manual 110

turning thereof, and as shown the body is provided with a polygonal extension 16, which is adapted to be engaged by the turning means E.

- 5 The turning means E as shown, simply includes a handle 17 and a head 19 provided with a polygonal shaped opening 20 for receiving the polygonal shaped extension 16. It is obvious, however, that a suitable 10 ratchet connection can be had between the head 19 of the turning means E and the head A if so desired, or that an ordinary hand brace attachment can be used with the head to turn the same.
- 15 The body 10 is provided with external threads 21 for a portion of its length for the reception of the adjusting sleeve D, which will be hereinafter more fully described.

The lower end of the adjusting bolt 12 is 20 provided with male threads 22 for the reception of an adjusting nut C which will now be described. The adjusting nut C comprises a disc shaped body 25 provided with an internally threaded axial bore 26 for the 25 threaded terminal 22 of the bolt 12 and its periphery is provided with equi-distantly spaced points with notches 27, which are in direct alignment with the slots 14 formed in the body 10 of the head A. The inner walls 30 of these notches are inclined as at 28 so as to conform to the configuration of the shanks of the jaws B, which will now be described.

As shown, the jaws B are three in number 35 and include the shanks 30 and the angularly related jaw faces 31 and 32. These jaw faces 31 and 32 are angularly related, so that when the jaws B are in any adjusted position, they can engage a hexagonal nut. 40 The upper terminals of the shanks 30 are provided with heads 33, which receive pins 34, which are adapted to fit in the annular groove 15, which forms a seat for the same, and permits the jaws to rock on said head. 45 The shanks 30 of the jaws extend downwardly at an incline from their circular heads 33 as at 35, at a point intermediate the portion 35 of the shanks and the jaw faces 31 and 32, the shanks 30 are bent outwardly 50 defining the angularly related arms 36 and 37. The angularly related arms 36 and 37 are adapted to conform to the internal configuration of the sleeve D which will be hereinafter more fully described. The arms 36 55 are adapted to be received in the notches 27 formed in the adjusting nut C as can be clearly seen by referring to Figure 7 of the drawings.

The adjusting sleeve D includes a hollow 60 cylindrical body 40, having internal threads 41 formed therein, a portion of its length for receiving the threads 21 formed on the body 10 to permit the longitudinal adjustment of the sleeve on said body. The inner 65 surface of the sleeve 40 directly below the

threads 41 is cut-out to provide the oppositely directly angularly disposed faces 43 and 44, which conform to the outer configuration of the arms 30 and 31.

In assembling the improved adjustable 70 socket wrench, the jaws B are placed within the grooves 14 formed in the body 10 of the head A, and the pins 34 thereof are placed within the groove 15. The nut C is then threaded on the threaded terminal 22 of the 75 bolt 12, after which the sleeve D can be threaded on the head. The wrench is now ready for use and can be readily turned by means of the means E or some other equivalent device.

In use of the improved wrench, the bolt 12 is turned so as to feed the nut C outwardly on the bolt 12 when it is desired to engage a relatively small nut, and the outward movement of the adjusting nut C permits 85 the jaws B to swing inwardly toward each other. The sleeve D is then rotated which will forcibly move the jaws B inwardly and bind the same into tight engagement with the nut, which precludes movement of the jaws, thereby permitting a firm grip to be had on the nut to be turned.

It can be seen that a relatively wide range of adjustment can be had, so that a number of different sized nuts can be acted upon and 90 thus the tool will effectively eliminate the necessity of providing a different sized head for each size of nut.

Changes in details may be made without departing from the spirit or scope of this 100 invention; but,

I claim:

1. In an adjustable socket wrench, a movable head, means connected with the head for actuating the same, a plurality of jaws pivoted to the head and arranged to extend outwardly from one face thereof, and adjustable means associated with the head for engaging the inside and outside faces of the jaws for adjusting the jaws relative to each other and for holding the said jaws in their adjusted position, the means for engaging the outside faces of the jaws being operable independently of the means engaging the inside faces of the jaws.

2. In an adjustable socket wrench, a rotatable head having external threads formed thereon for a portion of its length, a plurality of jaws pivoted to said head and arranged to extend below the lower face thereof, means for turning said head, an adjustable nut carried by the head and arranged to engage the inner surface of the jaws for moving the same outwardly, and an adjustable sleeve threaded on the head 125 movable independently of the movement of the adjustable nut to move the jaws inwardly and into clamping engagement with said nut.

3. In an adjustable socket wrench, a mov-

130

- able head, a plurality of jaws removably associated with the head for swinging movement, an adjustable nut member carried by the head for engaging the inner faces of the 5 jaws, an adjustable sleeve carried by the head movable independently of the movement of the adjustable nut to engage the outer surface of the jaws, and means for imparting movement to the head.
- 10 4. In an adjustable socket wrench, a cylindrical head having longitudinally extending grooves formed in the outer surface thereof and an annular groove communicating with the longitudinally extending grooves, a plurality 15 of removable jaws pivotally associated with said head including relatively long shanks, and angularly related jaw faces, the shanks including angularly related arms, and pivot pins carried by the upper terminals 20 of the arms arranged to detachably fit in said annular groove, the head having an axial bore, an operating member rotatably fitted in said bore, having the inner end thereof threaded, an actuating nut threaded upon the threaded terminal of the operating member and having inclined notches formed in the periphery thereof for receiving the arms of the shanks of the jaws, a sleeve threaded upon said head having the inner end thereof provided with a working 25 face for engaging the outer surface of the arms of the jaws, and an operating handle connected with said head.
5. In an adjustable socket wrench, a movable head, a plurality of jaws removably 30 associated with the head for swinging movement, movable means engaging the inner faces of the jaws to move them apart, and means independently operable of the first means, for moving said jaws toward each 35 other.

LOUIS ALBERT MORGAN.
